DESIGN FOR A GRAVE MARKER

Jonas E. Baker, Peabody, Kans.

Application March 17, 1933. Serial No. 47,494

Term of patent 3½ years

To all whom it may concern:

Be it known that JONAS E. BAKER, a citizen of the United States, residing at Peabody, in the county of Marion and State of Kansas, has invented a new, original, and ornamental Design for Grave Markers, of which the following is a specification, reference being had to the accompanying drawing, forming part thereof.

Referring to the drawing:

Fig. 1 is a front view of a grave marker, showing my new design.

Fig. 2 is a side view of Fig. 1.

I claim:

The ornamental design for a grave marker, as shown.

In testimony whereof I affix my signature.

JONAS E. BAKER.
